(57) **CLAIM**

The ornamental design for an automobile hood, as shown and described.

DESCRIPTION

FIG. 1 is perspective view from the front left side of an automobile hood showing my new design;

FIG. 2 is a top plan view;

FIG. 3 is a front elevation view; and,

FIG. 4 is side elevation view.

The rear view of the surface that faces the automobile's engine compartment when installed is omitted and is not part of the claimed design.
